CLAIM

Related U.S. Application Data

The design for a pouch for pencils or the like, as shown and described.

(62) Division of application No. 29/232,156, filed on Jun. 15, 2005, now Pat. No. Des. 535,470.

DESCRIPTION

(51) LOC (9) Cl. 03-01

FIG. 1 is a front perspective view of the pouch of the present invention;

(52) U.S. Cl. D3/206

FIG. 2 is a front view of the pouch.

(58) Field of Classification Search D3/273,

FIG. 3 is a front perspective view of another embodiment of the pouch of the present invention;

D3/206, 215, 294, 303, 315, 201, 221, 229,
D3/306; 206/349; D19/77, 81, 83, 85

FIG. 4 is a front view of the pouch of FIG. 3;

See application file for complete search history.

FIG. 5 is a front perspective view of another embodiment of the pouch of the present invention; and,

FIG. 6 is a front view of the pouch of FIG. 5.

(56) References Cited

The broken and dotted lines are for illustrative purposes only and do not constitute any part of the claimed design.

U.S. PATENT DOCUMENTS

The broken line showing of the zipper, the upper side and top edges of the pouch, and the vertical broken lines seen on each edge of the horizontal band, is included for the purpose of illustrating portions of environment of the pouch for pencils or the like and forms no part of the claimed design.
